UNITED STATES PATENT OFFICE.

REESE P. BALDWIN, OF COLLEGEVILLE, PENNSYLVANIA.

MANUAL MOTOR.

1,150,410.

Specification of Letters Patent. Patented Aug. 17, 1915.

Application filed July 18, 1914. Serial No. 851,740.

To all whom it may concern:

Be it known that I, REESE P. BALDWIN, a citizen of the United States, residing at Collegeville, in the county of Montgomery and 5 State of Pennsylvania, have invented a new and useful Manual Motor, of which the following is a specification.

The invention relates to improvements in manual motors or propelling mechanism for 10 vehicles, etc.

The object of the present invention is to improve the construction of manually operable propelling mechanism and to provide a simple, practical, and efficient construction, 15 designed primarily for propelling vehicles, boats, and other conveyances, and capable also of being advantageously employed for operating various mechanisms.

A further object of the invention is to 20 provide propelling or motor mechanism of this character, equipped with a rocking chair or seat, and capable of responding to the slightest movement of the same in either direction, whereby the mechanism may be 25 conveniently operated with a long or short stroke by the weight of a person, with little exertion.

It is also an object of the invention to provide an operating lever arranged in 30 convenient position with relation to the rocking chair or seat, and capable of operation independently thereof, and also of being actuated in conjunction therewith, and of assisting and facilitating the movement of the 35 rocking chair.

With these and other objects in view the invention consists in the construction and novel combination of parts hereinafter fully described, illustrated in the accompanying 40 drawings, and pointed out in the claims hereto appended, it being understood that various changes in the form, proportion, size and minor details of construction, within the scope of the claims, may be resorted 45 to without departing from the spirit or sacrificing any of the advantages of the invention.

In the drawings:—Figure 1 is a side elevation of a rockermobile equipped with propelling mechanism constructed in accordance with this invention. Fig. 2 is a transverse sectional view on the line 2—2 of Fig.

1. Fig. 3 is a vertical longitudinal sectional view taken substantially on the line 3—3 of Fig. 2. Fig. 4 is a plan view of the propelling mechanism, partly in section, and partly broken away. Fig. 5 is a horizontal sectional view, taken substantially on the line 5—5 of Fig. 3. Fig. 6 is a vertical sectional view illustrating the construction of 55 the ratchet and clutch mechanism. Fig. 7 is a horizontal sectional view of the same.

Like numerals of reference designate corresponding parts in all the figures of the drawings.

In the accompanying drawings, in which is illustrated one embodiment of the invention, the manually operable motor or propelling mechanism is shown applied to a rockermobile, but the manual motor or propelling mechanism may be advantageously 60 employed for operating various machines and devices.

The rockermobile comprises in its construction a frame 1 provided with front and 75 rear axles 2 and 3, on which are mounted front and rear wheels 4 and 5. The rear wheels are fixed to the rear axle, which is journaled in suitable bearings of the frame of the vehicle, and is driven by the propelling mechanism.

The machine, in practice, is designed to be equipped with suitable steering gear, and it may be made in the form of a toy automobile, as indicated in the accompanying 85 drawings, or be constructed in any other desired manner, as the propelling mechanism will be found both useful and advantageous for propelling various kinds of vehicles.

The rear axle has keyed or otherwise secured to it a sprocket pinion 6, which is connected by a sprocket chain 7 with a sprocket wheel 8 of a transverse shaft 9. The transverse shaft 9, which extends across 95 and is journaled in suitable bearings 10 of a casing 11, is connected by variable speed gearing with a transverse driving shaft 12. While it is preferable to employ sprocket 100 gearing for connecting the transverse shaft 9 with the rear axle, any other suitable gearing may be employed, and the said transverse shaft 9 may be geared with various machines and devices for operating the

same. The driving shaft extends across and is journaled in suitable bearings 13 of the casing 11, and while ball bearings are shown, the shafts may, of course, be mounted in any desired manner.

The variable speed gearing, which also may be of any preferred construction, is illustrated in the drawings as comprising spur gears 14, 15, and 16, keyed or otherwise fixed to the driving shaft, and shiftable spur gears 17, 18, and 19, mounted on and slidably interlocked with the transverse shaft 9. An intermediate gear 20 is interposed between the gears 14 and 17, and is continually in mesh with the gear 14, the gear 17 being carried into and out of mesh with the intermediate gear 20 by a horizontal shifting lever 21 extending longitudinally of the vehicle and fulcrumed intermediate of its ends at 22 at the front of the casing, exteriorly thereof.

The rear end 23 of the shifting lever 21 is forked and is provided with means for engaging a grooved hub extension 24 of the shiftable gear 17. The front arm of the shifting lever 21 is connected by a link 25 with an upright operating lever 26 fulcrumed at its lower end 27 and carrying a pawl or dog 28 for engaging a notched segment 29. The pawl or dog is controlled by a latch lever 30 mounted on the operating lever contiguous to the upper handle portion thereof. The gears 18 and 19 are connected by a sleeve 31 having an enlarged grooved portion 32, which is engaged by a forked rear end 33 of a shifting lever 34, arranged similarly to the shifting lever 21 and fulcrumed intermediate of its ends at 35 at the front of the casing. The shifting lever 34 is connected by a link 36 with an upright operating lever 37, fulcrumed at its lower end 38 and carrying a pawl or dog 39 for engaging a notched segment 40 and controlled by a latch lever 41. The operating levers 26 and 37 are located in advance of the rocking chair 42 in convenient position to be operated by a person occupying the seat 43 of the chair, but the said levers 26 and 37 may be located at any other convenient point, and in the simpler forms of the propelling or motor mechanism, variable speed gearing may be omitted.

The rocking chair has its rockers 44 arranged upon spaced longitudinal supporting bars or pieces 45, secured upon the top of the casing 11 at opposite sides thereof, but the rocking chair may be mounted in any other desired manner, and in practice, suitable means will be employed for preventing the rocking chair from sliding either laterally or longitudinally, when in motion. The rocking chair is equipped at the front and back with approximately L-shaped arms 46 and 47, consisting of upper portions extending longitudinally of the vehicle, and

outer depending portions, to which are secured the terminals 48 of a chain 49, but any other flexible connection may, of course, be employed. The terminal portions of the chain extend upwardly from the lower outer ends of the front and rear arms 46 and 47 and are arranged upon front and rear guide pulleys 50 and 51, journaled in suitable supports 52 and 53 at the front and back of the casing, as clearly illustrated in Fig. 3 of the drawings. The front and rear supports or standards 52 and 53 are preferably composed of spaced sides and a connecting top portion or chain, traveling over the pulleys and being confined thereon by the standards or supports. The chain, which extends between the rockers of the chair, is connected at an intermediate point with an upright oscillatory actuating lever 54, provided at its lower end with a head 55 and having a reduced upper terminal portion 56 extending through the opening in one of the links of the chain. The upper portion of the lever is adapted to play through the opening in the engaged link during the oscillation of the rocking chair, and when the chair is rocked, the chain is moved longitudinally over the guide pulleys and oscillates the lever 54. The head 55 of the lever, which is mounted on a pivot 57, is connected above and below the said pivot 57 by suitable pivots 58 and 59 with the rear ends of reciprocating links 60 and 61, which are pivotally connected at their front ends 62 and 63 with projecting lugs 64 and 65 of vibratory members or elements 66 and 67, which are circular and hollow and constitute sections of a cylindrical casing. The sections or members 66 and 67, which are provided with hub extensions 68 and 69, are mounted for partial rotary or pivotal movement on the driving shaft, and they incase a ratchet wheel 70 mounted for rotary movement on the driving shaft 12 and having a clutch connection therewith to permit the driving shaft to rotate forwardly independently of the actuating mechanism in descending a hill, and also when the vehicle has accumulated sufficient momentum to propel it without the aid of the actuating mechanism. The hollow circular reversely movable vibratory members or sections 66 and 67 are equipped with pawls or dogs 71, slidably mounted in tubular arms or housings 72 and pressed inwardly into engagement with the ratchet wheel by springs 73, the tension of which is regulated by screw plugs 74 mounted in the outer ends of the tubular arms or housings 72. The tubular arms or housings 72 are preferably formed integral with the vibratory sections or members 66 and 67, and the pawls or dogs 71, which are guided in the tubular arms, have hollow shanks 75 into which the coiled springs 73 extend. The ratchet wheel 70, 125

which is of a width to extend across the space within the vibratory sections or members, is provided at its periphery with ratchet teeth 76, of a length to be engaged by both sets of the pawls or dogs. The reciprocal links 60 and 61 are of unequal length to space the lugs at different points on the periphery of the ratchet wheel when the oscillatory lever is in an upright position, and the said lugs operate in different arcs. The ratchet wheel is preferably provided with twenty-five teeth, and each of the vibratory sections is preferably equipped with four pawls or dogs. With this arrangement, only one pawl or dog of a set engages the ratchet wheel, and the other pawls or dogs of such set, as clearly illustrated in Fig. 6 of the accompanying drawings, are located different distances from the teeth directly in advance of the said pawls or dogs. By this arrangement, it will be clear that the sets of pawls or dogs, in alternately engaging the ratchet wheel to produce a continuous forward rotation of the same, reduce the lost motion to a minimum, and the oscillatory lever is permitted to move only a fraction of the distance between the teeth of the ratchet wheel, before a tooth thereof is engaged by one of the pawls or dogs. This construction results in an exceedingly sensitive manual motor or propelling mechanism, and the leverage is such that the mechanism responds to the slightest rocking movement of the chair.

The clutch mechanism for connecting the ratchet wheel with the driving shaft comprises an inner clutch member 77 having a hub extension 78 keyed or otherwise secured to the driving shaft and constituting a journal for the ratchet wheel 70, which is provided in its outer side face with a recess 79 in which the inner clutch member operates. The recess 79 is circular and the ratchet wheel is provided at the said recess with an interior clutch face 80 consisting of a series of approximately semicircular recesses adapted to receive a roller 81 and cause the same to engage a straight edge or face 82 of the inner clutch member. The inner clutch member is provided at each of its sides with a straight edge or face 82, and in the form shown, three coating rollers 81 are provided. The inner clutch member is also provided at the rear terminals of the straight edges with hook-shaped engaging portions 83 forming seats for the rollers and adapted to pick the same up from the recesses 80 and carry the said rollers forwardly when the driving shaft rotates independently of the ratchet wheel.

No claim is made in the present application to the particular construction of the clutch, as various forms of clutches may be employed for connecting the ratchet wheel with the driving shaft.

The transverse shaft 9 is equipped with a ratchet wheel 84, which is engaged by pawls or teeth 85 of a pair of bars or members 86 extending forwardly from the ratchet wheel and pivotally connected at their front ends 87 to an operating lever 88 above and below the pivot 89 thereof. The operating lever is mounted at one side of the rocking chair at a point in advance of the same in convenient position to be grasped by a person occupying the seat of the rocking chair, and while the operating lever may be oscillated independently of the seat for actuating the vehicle, it is also adapted to be used in conjunction with the rocking chair, and will materially assist a person in such rocking movement. The operating lever forms a convenient place for the hand, and by the use of the lever, and with comparatively little exertion, the speed of the vehicle may be greatly accelerated. Also, by means of the hand operating lever, sufficient power may be easily applied to the propelling mechanism to enable the vehicle to ascend readily steep grades. When the lever is oscillated, one or the other of the bars or members 86 engages the ratchet wheel 85 and partially rotates the same, and a continuous forward rotary motion is imparted to the ratchet wheel 85.

The rocking chair is provided beneath its seat with a compartment 90, adapted to receive a weight for increasing the effect of the mechanism when desired. The seat, as shown in Fig. 4 of the drawings, is provided with a closure 91, adapted to afford access to the compartment 90, but the latter may be constructed and arranged in any other desired manner.

What is claimed is:

1. A device of the class described including a ratchet wheel, vibratory members provided with pawls or dogs arranged to engage the ratchet wheel for imparting a continuous rotary movement to the same, an oscillatory actuating lever, and links connected at one end with the vibratory members and at the other end with the lever at opposite sides of the fulcrum point thereof.

2. A device of the class described including a ratchet wheel, reversely movable vibratory members incasing the ratchet wheel and provided with interiorly arranged pawls or dogs engaging the same, and an oscillatory actuating lever connected at opposite sides of its pivotal point with the said members.

3. A device of the class described including a ratchet wheel, reversely movable hollow vibratory members fitted together and forming a substantially cylindrical casing in which the ratchet wheel is arranged, said members being provided with radially arranged tubular arms, spring actuated dogs mounted in the arms and arranged to en-

gage the ratchet wheel, an oscillatory lever, and links connected at one end with the said members and at the other end with the lever above and below the pivotal point thereof.

5 4. A device of the class described including a shaft, a ratchet wheel having a clutch connection with the shaft, reversely movable vibratory members mounted for rotary movement on the shaft and provided with 10 pawls or dogs for engaging the ratchet wheel, and an oscillatory lever connected above and below its pivotal point with the said members.

10 5. A device of the class described including a ratchet wheel, reversely movable vibratory pawls or dogs engaging the ratchet wheel, an oscillatory lever connected at opposite sides of its pivotal point with the 20 said pawls or dogs and adapted to impart a continuous rotary movement to the ratchet wheel, a rocking seat, and a longitudinally movable flexible connection connected with and actuated by the rocking seat, and also 25 connected with and actuating the lever.

30 6. A device of the class described including a ratchet wheel, reversely movable vibratory pawls or dogs engaging the ratchet wheel, an oscillatory lever connected at opposite sides of its pivotal point with the said pawls or dogs and adapted to impart a continuous rotary movement to the ratchet wheel, a rocking seat, and a longitudinally 35 movable flexible connection connected at its ends with the rocking seat and actuated by the same, said flexible connection being also connected at an intermediate point with the lever.

40 7. A device of the class described including a seat provided with rockers, spaced guiding means, a longitudinally movable flexible connection guided by the said means and connected with and actuated by the seat, an oscillatory lever connected with the said 45 flexible connection between the spaced guiding means, and mechanism connected with and actuated by the said lever.

50 8. A device of the class described including a seat provided with rockers and having front and rear arms, spaced guide pulleys, a longitudinally movable flexible connection on the guide pulleys and secured to the said arms, an oscillatory lever connected with the flexible connection at a point between the 55 said pulleys, and mechanism connected with and actuated by the said lever.

60 9. A device of the class described including spaced guide pulleys, a longitudinally movable flexible connection arranged on the guide pulleys and extended downwardly beyond the same, a seat having rockers and provided with front and rear arms having downwardly extending portions connected with the terminals of the flexible 65 connections, an oscillatory lever connected with the

flexible connection at a point between the guide pulleys, and mechanism connected with and actuated by the said lever.

10. A device of the class described including a ratchet wheel, an oscillatory lever, reversely movable pawls or dogs engaging the ratchet wheel and connected with the lever at opposite sides of the pivotal point thereof, a longitudinally movable flexible connection connected with the said lever, spaced 70 guiding means receiving the flexible connection and located in advance and in rear of the lever, and a seat provided with rockers and connected with the flexible connection and adapted to actuate the same. 80

11. A device of the class described including a rocking seat, mechanism actuated by the seat, a ratchet wheel, means for connecting the ratchet wheel with the said mechanism, a pivotally mounted hand operating lever, and bars or members pivotally connected to the lever at opposite sides of the fulcrum point and provided with means for engaging the ratchet wheel. 85

12. A device of the class described comprising a seat provided with rockers, mechanism connected with and actuated by the seat and including a clutch, a hand operating lever located in advance of the said seat for either independent or simultaneous 90 operation, a ratchet wheel, means for connecting the ratchet wheel with the said mechanism, and bars or members pivoted to the lever at opposite sides of the pivotal point thereof and provided with means for 95 engaging the ratchet wheel. 100

13. A device of the class described including a driving shaft, a rocking seat, means actuated by the rocking seat for rotating the driving shaft, said means including a clutch, 105 a transverse shaft, gearing connecting the shafts, a ratchet wheel mounted on the transverse shaft, an operating lever, and a link connected with the operating lever and provided with means for engaging the ratchet 110 wheel.

14. A device of the class described comprising a driving shaft, a seat provided with rockers, means actuated by the seat for rotating the driving shaft, said means including a clutch, a transverse shaft, a ratchet wheel mounted on the transverse shaft, a hand operating lever, links connected with the lever at opposite sides of the pivotal point thereof and provided with means for 115 engaging the ratchet wheel, and variable speed gearing connecting the said shafts. 120

15. A device of the class described including a driving shaft, a rocking seat, means actuated by the said seat for rotating the driving shaft, a transverse shaft, a hand lever, means actuated by the hand lever for directly rotating the transverse shaft, and gearing for connecting the transverse shaft 125 with the driving shaft. 130

16. A device of the class described including a ratchet wheel, reversely movable vibratory members, each provided with a plurality of pawls or dogs for engaging the ratchet wheel, an oscillatory actuating lever, and long and short links connected at one end to the lever at opposite sides of the pivotal point thereof.

In testimony, that I claim the foregoing as my own, I have hereto affixed my signature in the presence of two witnesses.
